UNITED STATES PATENT OFFICE.

PUTNAM MORRISON, OF CHATTANOOGA, TENNESSEE.

FASTENING DEVICE.

SPECIFICATION forming part of Letters Patent No. 764,487, dated July 5, 1904.

Application filed October 19, 1903. Serial No. 177,602. (No model.)

To all whom it may concern:

Be it known that I, PUTNAM MORRISON, a citizen of the United States, and a resident of Chattanooga, in the county of Hamilton and State of Tennessee, have invented a new and Improved Fastening Device, of which the following is a full, clear, and exact description.

The invention relates to knockdown furniture; and its object is to provide a new and improved device for fastening two parts or members of furniture, crates, packing-boxes, and other articles together without the use of screws, nails, or similar fastening means, the device being also serviceable as a support for shelves and the like.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement as applied. Fig. 2 is a face view of the blank for forming the connecting-key for the staples. Fig. 3 is a cross-section of the key, and Fig. 4 is a sectional side elevation of the same.

The fastening device consists, essentially, of a key A and receiving members B B', preferably in the form of staples driven into the parts C C' to be joined or fastened together, as plainly indicated in Fig. 1. The key A is preferably made from a single piece of sheet metal cut to form the blank shown in Fig. 2, which blank consists of a body A', adapted to be bent into angular form to fit the inner faces of the parts C C' at the corners thereof, and from the said body A' depend spaced arms A² A³ for engaging the receiving members B B', the inner edges A⁴ of the said arms A² A³ being tapering, so as to draw the parts C C' toward each other on driving the key home.

From the middle of the body A' of the blank extend upwardly flaps A⁵ A⁶, arranged one

alongside the other and adapted to be bent at right angles to the body A' after the latter is bent into angular shape as described, so that the flaps become superimposed, and then their ends are bent under or doubled up, so that the bent-up end of one flap engages the other flap, as will be readily understood by reference to Figs. 3 and 4.

By the arrangement described the flaps A⁵ A⁶ securely interlock with each other and produce a horizontally-disposed head for driving the key home in a downward direction, so by the blow of a hammer, or for disengaging the key from the receiving members B and B' on striking the head underneath in an upward direction by a hammer or other tool.

The head of the key is very strong and durable, as it is formed by the interlocked superimposed flaps A⁵ A⁶, extending integrally and at right angles from the angular body of the key, so that the said head can be used as a support for shelves and the like.

It is understood that the staples B and B' are driven into the parts C and C' in alignment with each other and properly spaced from the joint of the parts, so that when the key-arms A² A³ are inserted in the staples and the key is driven home then the beveled inner edges A⁴ act at the inner end of the staples so as to draw the parts C and C' firmly together, as previously mentioned.

The fastening device described takes up comparatively little room and serves to securely unite the parts and strengthen the same, especially as the angular body A and the arms A² A³ fit against the faces of the parts C and C'.

Having thus described my invention, I claim as new and desire to secure by Letters Patent—

1. A blank for a fastening device, formed from a single piece of sheet material and comprising a body having depending spaced arms with their inner edges tapering, and upwardly-extending flaps.

2. A fastening device comprising receiving members on the parts to be fastened together, and a key having a head and two arms stand-

ing at angles one to the other and adapted to engage the said receiving members, as set forth.

3. A fastening device comprising receiving members on the parts to be fastened together, and a key having a head and arms, said arms standing at right angles one to the other and adapted to engage the said receiving members, the said arms having tapering inner edges, as set forth.

4. A fastening device comprising receiving members secured to the parts to be fastened together, a key formed from a single piece of sheet metal and consisting of an angular body, two arms extending from the said body and adapted to engage the said receiving members, and a head formed by flanges extending

integrally from the said body and superimposed and interlocked with each other, as set forth.

20

5. A key for a fastening device, consisting of an angular body having depending arms, and a head formed of flanges, extending integrally from the body at right angles thereto, and superimposed and interlocked with each other, as set forth.

25

In testimony whereof I have signed my name to this specification in the presence of two subscribing witnesses.

PUTNAM MORRISON.
